INVENTOR

Otto H. Styles
by

Owen, Owen & Crampton.

UNITED STATES PATENT OFFICE.

OTTO H. STYLES, OF TOLEDO, OHIO.

PENCIL CALENDAR.

Application filed October 22, 1920. Serial No. 418,664.

To all whom it may concern:

Be it known that I, OTTO H. STYLES, a citizen of the United States, and a resident of Toledo, in the county of Lucas and State 5 of Ohio, have made an Invention Appertaining to Pencil Calendars; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 My invention has for its object to provide a novel calendar, having a pair of adjustable or rotative members on which are printed the months, the days of the week, and the dates of the month, whereby the 20 date of any particular day of a given year may be readily determined, and also whereby the dates of the days of any particular month may be indicated after the calendar has been set for determining the dates of 25 the days of any particular month.

The invention may be contained in structures of different forms, and to illustrate a practical application of the invention I have selected a calendar that may be readily 30 mounted on a pencil holder. The pencil calendar selected for purpose of illustration is shown in the accompanying drawings.

Figure 1 of the drawings illustrates a side view of the pencil calendar, and Fig. 2 illustrates the arrangement of the months, the 35 days of the weeks, and the dates of the days of the months, developed from the cylinders on which they are located as shown in Fig. 1.

1, Fig. 1 is the pencil, and 2 is the holder 40 into which the head or point of the pencil may be inserted in the manner well known in the art. The holder may be provided with the slots 3, and the tongues thus formed will frictionally engage the pencil to hold it in 45 the holder.

The holder is provided with a pair of beads 4 and 5, between which are located a pair of cylinders 6 and 7 that may be rotated on the holder and relative to each other. The 50 cylinders have printed thereon certain indicia which are inter-related so that when the figures or letters of one cylinder are placed in a certain position with reference to certain letters or figures of the other cylinder, 55 certain information is conveyed thereby. The letters or figures may be printed or

formed directly in the cylinders, or may be printed on sheet material such as paper, and secured to the cylinders.

In the construction shown, to form the 60 pencil calendar the cylinder 6 has the months of the year and the days of the week printed thereon in seven subdivided spaces extending, preferably, all the way around the cylinder. The month or months beginning 65 on each day of the week are located opposite the space in which the day of the week is designated for any particular year. In the construction shown, the calendar is for the year of 1921, and consequently the months 70 beginning on each day of the week are placed in the space in which is also located the day of the week, as for instance, May begins on Sunday, August on Monday, February, March and November begin on Tues- 75 day, June on Wednesday, September and December on Thursday, April and June on Friday, and January and October on Saturday. Moreover, the days of the week are placed in consecutive order around the cylinder, and are located at the edge of the cylinder 80 6 which adjoins an edge of the cylinder 7.

The cylinder 7 has printed thereon the numerals 1 to 31 inclusive, and the numbers 85 are likewise located in seven spaces extending around the cylinder, and into which the cylinder 7 is also subdivided. The numerals will thus follow in sequence of numbering, the days of the week located at the adjoining edge of the cylinder 6. Thirty-one 90 numerals are placed on the cylinder 7 so as to cover the number of days in the longer months such as May, August, etc. On cylinder 6 may also be printed the number of 95 days each month has, for convenience of reference.

In using the calendar one of the numerals is placed opposite or in alignment with one of the days of the week which the numeral 100 correctly designates as the day of that month, and the other numerals will correctly designate the other days of that month. Preferably, and as a rule, the numeral 1 is placed opposite or in alignment with the 105 day of the week located in the space, or opposite the space, or in alignment with the space in which the name of the month occurs, and since the names of the months are located in the spaces in alignment with 110 the days of the week on which they begin, the numeral 1 will correctly designate the

first day of that month, and consequently the other days of the month will be correctly designated by the numerals on the cylinder 7.

5 The year for which the calendar is designed may also be printed on the cylinder 6 and a description of the manner in which the calendar is to be used may be printed on the cylinder 7.

10 Having thus described my invention, what I claim as new, and desire to secure by Letters Patent, is,—

15 In a pencil calendar a cylinder having a slotted end for removably engaging with the end of the pencil, and having a pair of beads, a pair of cylinders rotatably supported on the first named cylinder and located between the beads, one of the second named cylinders having printed thereon the days

of the week along the edge adjoining the other of the second named cylinders, and the months of the year and the number of days of the months printed opposite the days of the week on which the months begin, the said cylinder also having the year for 25 which the calendar is to be used printed thereon, and the other cylinder having numerals corresponding to the days of the longer months divided into seven groups, the numerals in each group extending along 30 the cylinder and corresponding to the days of the month to designate the dates of the month occurring on the same day of consecutive weeks.

In testimony whereof, I have hereunto 35 signed my name to this specification.

OTTO H. STYLES.
